UNITED STATES PATENT OFFICE.

JOHN PERKINS, OF LIBERTY, INDIANA.

AIR CONTROL FOR DRAIN TILE.

Application filed March 21, 1921. Serial No. 453,931.

To all whom it may concern:

Be it known that I, JOHN PERKINS, a citizen of the United States, residing at Liberty, in the county of Union and State 5 of Indiana, have invented certain new and useful Improvements in Air Controls for Drain Tile, of which the following is a specification.

This invention relates to air control for 10 drain tile, and the main feature of the invention is the provision of means for excluding air from the tile when a large amount of water is flowing therethrough so as to prevent the air from displacing the 15 water, consequently the full capacity of the tile may be used for carrying the water.

A further feature of the invention is the provision of vents in the length of the drain for permitting air to readily enter 20 the drain at times when there is no water in the drain so as to aerate the soil and force moisture towards the top of the ground, said vents being so arranged as to provide drain openings at points where 25 bodies of water are inclined to rapidly collect, as after a heavy rain, thereby more rapidly removing the water from the top of the soil.

Other objects and advantages will be 30 hereinafter more fully set forth and pointed out in the accompanying specification.

In the accompanying drawings,

Figure 1 is a sectional view showing a tile drain with the air controlling means 35 attached thereto, and

Figure 2 is a vertical longitudinal sectional view through the air controlling means.

Referring to the drawings in which similar reference numerals designate corresponding parts throughout the several views, 40 1 indicates a drain which is preferably formed of tile, such as are constructed of burned clay, cement or the like and used 45 for draining soil, especially on farms, said drain being placed a suitable distance below the surface of the ground and covered over, the water entering the soil being attracted to the tile to some extent by suction created 50 by the flowing water. It has been found, however, that air in the ordinary drain displaces a certain amount of the water, consequently reducing the carrying capacity of the drain, and in order to overcome this 55 objectionable feature insert sections 2 are placed at intervals along the line of the

drain, each insert section serving as one of the tile, and in the upper wall of the insert section is formed a cavity 3 by bowing up the wall of the insert section at this point, 60 and in said cavity is pivotally mounted a valve 4, the pivot point 5 for the valve being so positioned that the valve will be nearly but not quite balanced. The end of the valve towards the outlet of the drain 65 is provided with an upwardly extending flange 6 which when the water strikes the under face of the valve moves upwardly and contacts with the wall of the cavity, thereby forming a partial seal in the drain 70 at this point and preventing air from passing upwardly through the drain from the outlet end thereof. Also formed in each insert section, and preferably in the rear of the valve, is an opening 7 which is surrounded by a neck 8 and over said neck is positioned a pipe section 9, said pipe section extending upwardly towards the surface of the soil, the upper end of the pipe section entering a basin 10. The wall of 80 the basin 10 is preferably constructed of cement and as the upper end of the basin projects slightly above the surface of the ground said wall is so inclined and shaped and so reinforced that it will not be easily 85 broken by being struck by farm implements, the implements glancing off and consequently readily passing around the basin. The major portion of the basin is buried in the ground and foreign particles are prevented 90 from entering the basin from the upper end by extending rods 11 across the opening in the upper end of the basin. The upper end of the pipe section 9 preferably extends a sufficient distance above the lower end of 95 the basin 10 so that any foreign particles that might enter the basin will be caught or trapped at this point, consequently they will not flow into the drain.

Where the drain passes through a low 100 section of land or points where water rapidly collects after a more or less heavy rain, the top of the basin 10 is positioned almost flush with the top of the soil, consequently the water will flow directly into the basin 105 and through the pipe section into the drain, thereby more rapidly carrying off the water.

By providing the vent and preferably placing the same in the rear of the valve any air within the drain after the water 110 has risen sufficiently within the drain to close the valve will flow out of the vent

opening formed by the pipe section and basin, and as a very limited amount of air can enter from the open end of the drain the water will fill the drain to substantially its full capacity. There are any number of the vent openings provided along the length of the drain and these vents are preferably placed a uniform distance apart each having an adjacent valve so that an excess amount of air will be excluded the full length of the drain, thereby materially increasing the capacity of the drain for carrying off the water.

As soon as the water recedes in the drain the valve will open by gravity, the additional weight of the flange 6 being sufficient to overbalance the valve and cause that end of the valve to which the flange is attached to descend, although the overbalancing weight is not such as will retard the action of the valve when water rises within the drain and strikes the under face of the valve.

By excluding the excess amount of air from the drain and permitting all parts of the drain to fill with water, the suction created by the flowing water will be greatly increased, consequently the water seeping through the soil will be drawn into the drain from a greater distance than would be possible if the excess amount of air was not excluded from the drain, and the greater the volume of water in the upper end of the drain the faster the water will travel toward the outlet.

Having thus fully described my said invention, what I claim as new and desire to secure by Letters Patent, is:

1. An air controlling means for a drain comprising an insert section adapted to replace one member of the drain, a pipe section extending upwardly from said insert section, a basin surrounding the upper end of said pipe, a valve pivotally mounted in said insert section, and means on one end of said valve for preventing inward passage of air through said drain when the end of said valve is elevated.

2. An air control for drains comprising a hollow section inserted in the line of the drain to form a part thereof, a vent extending from said inserted section to the outer atmosphere, a valve pivotally mounted in said insert section one end of which is movable upwardly when influenced by pressure of water thereagainst and an upwardly extending flange on the valve adapted to be moved against the wall of said inserted section when the end of said valve is raised for preventing the entrance of air into the drain above the water.

3. An air control for drains comprising a hollow section intersecting and forming a part of the drain, a pipe projecting upwardly from said insert section and communicating therewith, a tapered basin surrounding the upper end of said pipe and extending upwardly to the surface of the soil, the lower end of said basin being larger in diameter than the diameter of said pipe and terminating below the upper end of said pipe for forming a trap for excluding foreign particles from the open end of said basin, and a pressure operated valve in said insert section having means thereon for excluding the passage of excess air through the drain when closed.

4. An air control for drains comprising a hollow insert section adapted to intersect and form a part of said drain, an air vent extending from said insert section to the surface of the soil above the drain, a valve pivotally mounted in said insert section, and a flange at one end of said valve adapted to engage the wall of the insert section and prevent air from entering the drain when the valve is closed.

In witness whereof, I have hereunto set my hand and seal at Liberty, Indiana, this 24th day of February, A. D. nineteen hundred and twenty-one.

JOHN PERKINS. [L. S.]
